(57) **CLAIM**

The ornamental design for a scarf, as shown and described.

DESCRIPTION

FIG. 1 is a perspective view of a scarf according to the first embodiment;

FIG. 2 is an alternative perspective view thereof;

FIG. 3 is a first side elevation view thereof;

FIG. 4 is a front elevation view thereof;

FIG. 5 is a second side elevation view thereof;

FIG. 6 is a rear elevation view thereof;

FIG. 7 is a top plan view thereof;

FIG. 8 is a bottom plan view thereof;

FIG. 9 is a front perspective view thereof, in use;

FIG. 10 is a rear perspective view thereof, in use;

FIG. 11 is a perspective view of the scarf according to the second embodiment;

FIG. 12 is an alternative perspective view thereof;

FIG. 13 is a first side elevation view thereof;

FIG. 14 is a front elevation view thereof;

FIG. 15 is a second side elevation view thereof;

FIG. 16 is a rear elevation view thereof;

FIG. 17 is a top plan view thereof;

FIG. 18 is a bottom plan view thereof;

FIG. 19 is a front perspective view thereof, in use;

FIG. 20 is a rear perspective view thereof, in use;

FIG. 21 is a perspective view of the scarf according to the third embodiment;

FIG. 22 is an alternative perspective view thereof;

FIG. 23 is a first side elevation view thereof;

FIG. 24 is a front elevation view thereof;

FIG. 25 is a second side elevation view thereof;

FIG. 26 is a rear elevation view thereof;

FIG. 27 is a top plan view thereof;

FIG. 28 is a bottom plan view thereof;

FIG. 29 is a front perspective view thereof, in use;

FIG. 30 is a rear perspective view thereof, in use; and,

FIG. 31 is an enlarged detail view thereof, showing a zippered pocket in an open position.

(Continued)

The break-away lines shown in FIGS. 1-3, 5, 7, 8, 11-13, 15, 17, 18, 21-23, 25, 27 and 28 indicate that any portion of the article beyond what is shown forms no part of the claimed design. The broken lines shown in FIG. 31 represents the bounds of the claim and do not form part of the claimed design. The partial human figure shown in FIGS. 9, 10, 19, 20, 29 and 30 represent how the claimed design may appear when in use and forms no part of the claimed design. The zippered pocket environment shown in FIGS. 11, 14, 17 and 19 form no part of the claimed design.

1 Claim, 16 Drawing Sheets
